UNITED STATES PATENT OFFICE.

JAMES TREGURTHA, OF MALDEN, ASSIGNOR, BY MESNE ASSIGNMENTS, TO
THE ADJUSTABLE TELEPHONE SUPPORT COMPANY, OF BOSTON, MASS.

TELEPHONE-SWITCH.

SPECIFICATION forming part of Letters Patent No. 289,321, dated November 27, 1883.

Application filed May 14, 1883. (No model.)

To all whom it may concern:

Be it known that I, JAMES TREGURTHA, of Malden, in the county of Middlesex and State of Massachusetts, have invented certain new and useful Improvements in Telephonic Switches, of which the following is a full, clear, and exact description.

In this invention, in substance, as it is best to employ it, and as it is particularly illustrated in the drawings and hereinafter described, the telephonic receiver at all times, and whether in or out of use, is carried by an arm arranged to be moved forward and backward upon another arm or support therefor, and this moving arm and its support and connecting mechanism make the telephone-switch of this invention, and the attachment of the receiver to said moving arm is more a matter of convenience than of necessity in the operation and use of the switch, as will hereinafter fully appear.

The support for the moving arm of the switch carries a series of studs or posts, all insulated therefrom, but connected with the call and telephonic circuits, and said moving arm is linked or connected to a switching lever or plate, but insulated therefrom, and it and said switching-lever are arranged and adapted in such a manner that a movement of said arm 30 in one direction, and in that direction against a spring, so operates said switching-lever as through it to disconnect the call-circuit from the main line, being in the receiver and secondary circuit of the transmitter, and at the same time complete the primary local circuit of the transmitter, while a movement of said arm in the other direction, and in that direction from a reaction of said spring, cuts out the receiver and secondary circuit of the transmitter and restores the call-circuit.

This invention, in addition to the above, consists of other improvements, which will hereinafter fully appear.

In the accompanying plate of drawings a 45 telephonic switch of the present improved construction is illustrated in connection with a stand for telephonic instruments of the construction and arrangement of parts such as fully shown and described in my application 50 for Letters Patent filed March 26, 1883; but it

is not intended to limit this invention thereto, for, as will appear from the description in detail which follows, it is capable of application to stands of other construction and arrangement of parts—as, for instance, to the box containing the call mechanism of the telephone; and in the drawings—

Figure 1 is a plan view of the telephone-switch and its stand. Fig. 2 is a side elevation in one part broken out and in vertical section. Fig. 3 is a horizontal section and plan view enlarged, as will appear hereinafter. Fig. 4 is a longitudinal vertical section on line 4-4, Fig. 3. Fig. 5 is a transverse vertical section on line 5-5, Fig. 3. Fig. 6 is a transverse vertical section, enlarged, on line 6-6, Fig. 1. Fig. 7 is a plan view, and Fig. 8 is a longitudinal vertical section on line 8-8, Fig. 7, illustrating a modification. Fig. 9 is a diagram in illustration of the improved telephone switch, with the wire-connections for primary and secondary circuit through the transmitter and receiver, and a call, main line, and local-battery circuits. Fig. 10 is a vertical section, and Fig. 11 is a plan view in detail, to be hereinafter particularly referred to.

In the drawings and diagram, A is the telephonic transmitter, B the telephonic receiver, C a local battery, D a magneto-machine, and E call-bells, and each and all of any of 80 the usual constructions and arrangements of parts, and therefore needing no particular description herein.

The body portion of the receiver B is surrounded by clamp-ring F, in two parts, having ear-pieces a a, by which it is secured by screws to an outer lift, d, of a hinge composed of three lifts or leaves, d, e, and f, joined together by a common axial bolt, and the outer lifts, d and f, joined to each other by an interlocking pin, g, all so that the outer lifts can turn as one and the middle lift can turn of itself upon the axial bolt, and each of such turnings be independent of the other. Said middle lift, e, of the hinge above described is connected to the outer lift, k, of another hinge, which is in three leaves, k, l, and m, similarly connected and turning in its several lifts, but arranged to work in a plane at an angle to the hinge first described, and this 90 95 100

second hinge is connected by its middle lift, *l*, to an arm, *F*, which, between its two ends, has a fulcrum, *h*, in another arm, *G*, and is thus adapted to be swung forward and backward upon said latter arm. The supporting-arm *G* is carried by hinges arranged at an angle to each other, and each hinge is in three lifts, *n*, *q*, and *r*, of similar construction to the hinges previously described, and one of them is connected to the upper end of a vertical standard or rod, *H*, which is carried at the outer end of the horizontal continuation *J* of a vertical rod, *K*, arranged to be adjusted as to height and to be swung around a center, and for attachment to a bench or other suitable fixture, all, except as to the swing of the arm *F*, carrying the receiver upon the supporting-arm *G* therefor, as fully described and shown in the application aforesaid, and which, as it forms no part of the present invention, it is not deemed necessary to herein more particularly describe. The swing of the receiver-carrying arm *F* is in a plane coincident with its longitudinal axis and parallel with the same axis of its supporting-arm *G*, and its part *L*, extending beyond the fulcrum *h*, passes in said swing of the arm *F* across the supporting-arm *G*.

The supporting-arm *G* is provided with five studs or posts, marked with figures 1, 2, 3, 4, and 5, respectively, stud or post 1 being situated between studs 2 and 3, which are alongside and separated from each other, and studs 4 and 5 alongside of and separated from each other. Each of the studs 1, 2, 3, 4, and 5 is made of metal or other material suitable for an electric conductor. Again, each is suitably constructed for the attachment of an electric conducting-wire, and they are severally insulated from the support *G* by a common plate or stand, *A*², of insulating material—such as hard vulcanized india-rubber—which is attached to said support in any suitable manner, and, except as hereinafter described, said studs and posts have no electric communication with each other. The wire-connections between these several studs 1, 2, 3, 4, and 5 and a telephonic receiver, *B*, a telephonic transmitter, *A*, local battery *C*, bells *E*, magneto-machine *D*, ground at *M* and *N*, and main line *O* are shown in the diagram. These wires consist of a wire, *P*, connecting stud 1 with the main line *O*; a wire, *Q*, connecting stud 2 with bells *E*, magneto-machine *D*, and ground at *M*; a wire, *R*, running from stud 3 into and out of the receiver *B*, and thence into and out of the transmitter *A* to the ground at *N*; a wire, *S*, running from one pole of the local battery *C* to the primary coil of the transmitter, thence by a wire, *T*, to stud 5, and by a wire, *U*, from stud 4 to the other pole of said battery.

*B*² is an arm attached to and insulated from the swinging arm *F*, and interlocking at its end *t* with the notch *u* of a horizontal switching-plate, *C*², turning upon a fulcrum-pin, *v*,

of the block or plate *A*², of insulating material. The switching-plate *C*² is made of metal or other suitable electric conducting material, and it passes between the studs or posts 2, 3, 4, 70 and 5 and along its two edges, as at *w*, *x*, *y*, and *z*. It is shaped so that if the receiver-arm *F* be swung upon its fulcrum *h* in one direction (the switching-plate *C*² being operated thereby) the part *z* of said switching-plate 75 will come into contact with the side of stud or post 2, and its other parts—to wit, *w*, *y*, and *x*—be placed out of the direct contact, respectively, either with the posts or studs 3, 4, and 5, or with metallic or other electric conducting plates or surfaces *a*², attached to said studs or posts, as shown, and so that if the receiver-arm *F* be swung upon its fulcrum in the opposite direction (the switching-plate being operated thereby) the part *w* of said switching-plate 80 *C*² will come into direct contact with the side of stud or post 3, the part *y* with the side of post 4, and the part *x* with the side of post 5, or in the case of each of said posts or studs, as is particularly shown in the drawings, in 85 contact with the metal plate or surface *a*², attached thereto, respectively, by riding or passing over the same, and the part *z* of said switching-plate will be placed out of contact with the stud or post 2. Stud or post 1, as 90 shown in Figs. 1, 2, 4, 5, and 6, has an extension or arm, *b*², of metal or other suitable electric conducting material, which is shaped at its end to rest with a yielding pressure upon, and thus make contact with, the upper surface of 95 the metal switching-plate *C*². This post or stud 1, as shown in Figs. 7 and 8, makes the fulcrum *v* for the switching-plate *C*², and thus it is in contact therewith, dispensing with the necessity of the extension or arm *b*², above 100 described.

The several wire-connections between the several studs or posts 1, 2, 3, 4, and 5 and the receiver *B*, transmitter *A*, local battery *C*, bells *E*, magneto-machine *D*, ground at *M* and *N*, and main line *O* are, as usual, and together with a switching-plate of the construction, arrangement, and operation shown and described as to contact between its parts *w*, *x*, *y*, and *z* and said studs or metallic plates or surfaces 105 *a*² connected therewith, and together with a metal connection, either by the extension or arm *b*² or by the post 1 between said switching-plate *C*² and said post 1, established, first, with the switching-plate *C*² in contact 110 with stud 2 and said switching-plate out of contact with studs 3, 4, and 5, the call-circuit with the main line—that is, from main line *O* along wire *P* to stud 1 in the direction of the arrows marked with figure 1, and thence through 115 stud 2 along wire *Q* in the direction of the arrows marked with figure 2 to the bells *E*, magneto-machine *D*, and ground at *M*, and they establish, second, with the switching-plate 120 in contact with studs 3, 4, and 5—or, what is 125 the same thing, in contact with the metallic plates or surfaces *a*², respectively, of said

studs—and said switching-plate in contact with stud 3, the telephonic circuit with the main line O—that is, from main line O along wire P in the direction of the arrows marked 5 with the figure 1 to stud 1, and through said stud 1 to and through stud 3, and thence by wire R in the direction of the arrows marked with figure 3, to and through the receiver and transmitter, and from thence to the ground; 10 and, also, they then establish another circuit by wire T from the primary coil of the transmitter to and through stud 5, and from thence by the switching-plate C², through stud 4 and wire U and both poles of local battery C and wire S, with the transmitter A, thus completing the circuit between the transmitter A, 15 receiver B, and local battery C.

When, by bringing switching-plate C² into contact with stud 2, the call-circuit is established, the telephonic and other circuits above described as made at the same time with said telephonic circuit are broken; and, again, when, by bringing switching-plate C² into the contact described with the posts or studs 3, 4, 20 and 5, the telephonic and other circuits above described as made at the same time with said telephonic circuit are established, the call-circuit is broken; and either of these two classes of circuits is established, as the case may be, 25 by swinging the arm F in the one or the other direction upon its fulcrum h, and through the swing of said arm swinging the switching-plate C²; and these operations obviously are each capable of being accomplished without 30 removal of the receiver from said arm F—or, in other words, from its support—and either by pressure upon the arm F from the hand of the user or from the rest of the ear of the user against the receiver when being used. The 35 carrying-arm F for the receiver has a spring, W, coiled around its fulcrum-pin h within the shell or tubular casing X of the support G, surrounding said pin, and one end of said spring is attached to said fulcrum-pin h and the other end to said casing, all as plainly 40 shown in Fig. 2 of the drawings. This arrangement of the spring is such that the movement of the receiver-arm F in the one direction, as herein described, to break the call-circuit and establish the telephonic and other 45 circuits will be against said spring, and that the movement of said arm in the other direction, as herein described, to establish the call-circuit and break the telephonic and other circuits 50 will be from the reaction of said spring, whereby, as is apparent, all liability of the call-circuit being accidentally left broken or cut out when ceasing to use the telephone or 55 when it is not being used is obviated, absolutely.

The supporting-arm G for the receiver-carrying arm F has a fender or guard, Y, projecting therefrom on opposite sides of the receiver-carrying arm F, and in position to respectively abut against said arm F as it is 60 swung to make the contacts described between

the switching-plate C² and the studs or posts 2, 3, 4, and 5, and at the time such contacts are made, and thus by such abutments thereof prevent any undue strain or pressure between 70 the switching-plate and the studs when contact is made by them either for the call-circuit or for the telephonic and other circuits herein described. These fenders or guards Y may be upon the swinging arm F, in lieu of, upon 75 the supporting-arm G, as particularly shown and described. If desired, the carrying-arm F for the receiver, together with the supporting-arm G therefor, may be arranged for the one to have a rectilinear movement upon the 80 other, instead of a swinging movement, as has been herein particularly described and shown.

The studs or posts 4 and 5 may be dispensed with, thus dispensing with the local-battery and other circuits established through them 85 with the switching-plate C² in contact therewith; but it is preferable, for obvious reasons, to employ them.

The parts w, x, and y of the switching-plate C², making the electric connections between 90 said plate and the posts or studs 3, 4, and 5 and securing the establishment of the telephonic and other circuits, as has been described, are each shaped, together with the metal plates a² of said posts belonging to them 95 all, as shown, so that contact will be maintained at or insured between said parts of the switching-plate and said plates a² of the posts until the switching-plate has almost, in fact, reached the extreme limit of its swing to break said 100 telephonic and other circuits, the advantage of which is obvious in the use of the receiver and transmitter, as it allows the rest of the ear against the receiver to be relieved either accidentally or intentionally as it and the transmitter are being used without necessarily 105 breaking the circuit previously established for their being used.

A great advantage of the present improved telephonic switch is in the fact that, as all the 110 wire-connections are made with studs upon the support G and with no stud or studs upon the receiver-carrying arm F², there is no danger of the wires becoming entangled or interfering in any way with the use of said arm; 115 and, again, it allows the posts to be boxed or cased, thus protecting them against liability of injury from any cause whatever.

In Figs. 10 and 11, a⁴ is a horizontal rod that passes through and from side to side of the 120 block A², supporting or carrying binding-post 1 and other posts, and also that passes across and at its middle and cam or eccentric portion b⁴ in contact with the under side of the extension or finger piece b², hereinbefore described, 125 and making the electric connection between said post 1 and the switching-plate C². This eccentric b⁴ and rod a⁴ are arranged to be turned freely within said block A², and, for convenience in turning them, the rod has at one of 130 its projecting ends a milled head, d⁴, and it is shouldered at both projecting ends, to hold it

as it is turned against escape from said block. This eccentric b^4 is shaped so that, turned in one direction partially around, it will, by working against the under side of said extension b^2 , lift said extension sufficiently to break its rest upon and electric connection with said switching-plate C^2 , and also hold it thus lifted as long as said eccentric remains stationary and in such position relative to its said extension, when, 10 by continuing to turn the eccentric in the same direction, it will allow said extension b^2 to drop or move to its said rest and bearing upon said switching-plate, re-establishing electric connection between said switching-plate and post 15 1, which may be continued so long as said eccentric then remains in such position relative to said extension.

An eccentric, b^4 , constructed and arranged 20 and operating upon said extension b^2 as above described, plainly permits, by a simple turning of it, the telephonic instruments to be at any time instantly and completely put out of and into electric connection, thereby providing most efficient and ready means of making the instruments safe against accidents and casualties during electrical storms, and also during and at such other times as may be desired.

While the arm F, making the lever, as it were, 30 for operating the mechanism of the telephone-switch, has been herein particularly described and shown as carrying the telephone-receiver, and with manifest advantages and conveniences, it is plain that the telephone-receiver 35 may be removed therefrom and be carried and supported independently thereof, and without in the least degree affecting the operation of the switching mechanism by and from the movement of the switch arm or lever F upon 40 its support. Therefore it is not intended to limit this invention in any respect to the fact that said arm F, as particularly shown and described, does carry said receiver, although, as is obvious, it is preferable that it should, 45 and for that reason has been so particularly shown and described.

Having thus described my invention, what I claim, and desire to secure by Letters Patent, 50 is—

1. An arm, F, adapted for a forward and backward movement upon a support, G, in combination with the studs 1, 2, and 3, applied to said support, and with the switching-plate C^2 upon said support, adapted to be 55 operated by said moving arm, and insulated from said arm and support, but electrically connected with stud 1, and said studs 2 and 3, with the call and transmitter circuits, the latter circuits including the receiver, but all 60 insulated from said support, whereby by moving through said arm F said switching-plate in one direction the receiver and transmitter circuits will be established and the call-circuit broken, and by similarly moving said 65 switching-plate in the other and opposite direction the receiver and transmitter circuits will be cut out and the call-circuit established.

2. An arm, F, adapted for a forward and backward movement upon a support, G, and provided with a spring, W, in combination 70 with the studs 1, 2, and 3, applied to said support, and with the switching-plate C^2 upon said support, adapted to be operated by said moving arm, and insulated from said arm and support, but electrically connected with 75 stud 1, and said studs 2 and 3, with the call and transmitter circuits, the latter circuit including the receiver, but all insulated from said support, whereby by moving through said arm said switching-plate in one direction against said spring the receiver and 80 transmitter circuits will be established and the call-circuit broken, and by similarly moving said switching-plate in the other and opposite direction from the reaction of said 85 spring the receiver and transmitter circuits will be cut out and the call-circuit established.

3. An arm, F, adapted for a forward and backward movement upon a support, G, in combination with a fender or fenders or 90 guards, Y, and with studs 1, 2, and 3, applied to said support, and with the switching-plate C^2 upon said support, adapted to be operated by said moving arm, and insulated from said arm and support, but electrically 95 connected with stud 1, and said studs 2 and 3, with the call and transmitter circuits, the latter circuit including the receiver, but all insulated from said support, whereby by moving through said arm said switching-plate 100 in one direction the receiver and transmitter circuits will be established and the call-circuits broken, and by similarly moving said switching-plate in the other and opposite direction the receiver and transmitter circuits 105 will be cut out and the call-circuits established, and in either or both of said movements, through an abutment of said fender or fenders, said studs and switching-plate will be protected against undue pressure and strain. 110

4. An arm, F, adapted for a forward and backward movement upon a support, G, in combination with the studs 1, 2, 3, 4, and 5, applied to said support, and with the switching-plate C^2 upon said support, adapted to be 115 operated by said moving arm, and insulated from said arm and support, but electrically connected with stud 1, and said studs 2 and 3, with the call and transmitter circuits, the latter circuit including the receiver, and 120 said studs 4 and 5 connected with the circuit through a local battery, but all insulated from said support, whereby by moving through said arm F said switching-plate in one direction the receiver and transmitter and local- 125 battery circuits will be established and the call-circuit broken, and by similarly moving said switching-plate in the other and opposite direction the receiver and transmitter and local-battery circuits will be cut out and the 130 call-circuit established.

5. An arm, F, adapted for a forward and backward movement upon a support, G, and provided with a spring, W, in combination

with the studs 1, 2, 3, 4, and 5, applied to said support, and with the switching-plate C² upon said support, adapted to be operated by said moving arm, and insulated from said arm 5 and support, but electrically connected with stud 1, and said studs 2 and 3, with the call and transmitter circuits, the latter circuit including the receiver, and said studs 4 and 5 connected with a circuit through a local battery, but all insulated from said support, whereby by moving through said arm said switching-plate in one direction against said spring the receiver and transmitter and local-battery circuits will be established and the 10 call-circuit broken, and by similarly moving said switching-plate in the other and opposite direction from the reaction of said spring the receiver and transmitter and local-battery circuits will be cut out and the call-circuit established.

6. The arm F, moving upon a support, G, having studs 1, 2, and 3, electrically connected, substantially as described, in combination with a switching-plate, C², electrically connected, as described, with stud 1, and constructed at its parts w and z, and arranged to be operated by said arm F, and all so as to make contact with studs 2 and 3, substantially as and for the purpose described.

30 7. The arm F, moving on a support, G, having studs 1, 2, 3, 4, and 5, electrically con-

nected, substantially as described, in combination with a switching-plate, C², electrically connected with stud 1, and constructed at its parts w, x, y, and z, and arranged to be operated by said arm F, and all so as to make contact with studs 2, 3, 4, and 5, substantially as and for the purpose described.

8. An arm, F, moving upon a support, G, having studs 1, 2, and 3, electrically connected, substantially as described, in combination with a switching-plate, C², operated by said arm F, and electrically connected to stud 1 through an extension or arm, b², substantially as described, for the purposes specified.

9. An arm, F, moving upon a support, G, having studs 1, 2, and 3, electrically connected, substantially as described, in combination with a switching-plate, C², operated by said arm F, and electrically connected to stud 1 through an extension or arm, b², which is adapted to be placed into and out of said electrical connection, substantially as described, for the purposes specified.

In testimony whereof I have hereunto set 55 my hand in the presence of two subscribing witnesses.

JAMES TREGURTHA.
